(57) **CLAIM**

The ornamental design for a refrigeration compressor, as shown and described.

DESCRIPTION

FIG. 1 is a left side elevational view of the refrigeration compressor;

FIG. 2 is a top plan view of the refrigeration compressor;

FIG. 3 is a right side elevational view of the refrigeration compressor;

FIG. 4 is a bottom plan view of the refrigeration compressor;

FIG. 5 is a front end elevational view of the refrigeration compressor;

FIG. 6 is a rear end elevational view of the refrigeration compressor;

FIG. 7 is a perspective view from behind and above of the refrigeration compressor; and,

FIG. 8 is a perspective view from in front and above of the refrigeration compressor.
